UNITED STATES PATENT OFFICE.

AUGUST OTTO TANNENBERG, OF NEW ORLEANS, LOUISIANA, ASSIGNOR TO
WILLIAM H. BOFINGER, OF SAME PLACE.

COMBINED SIDE AND CENTER BRACE ATTACHMENT FOR STEP-LADDERS.

SPECIFICATION forming part of Letters Patent No. 485,900, dated November 8, 1892.

Application filed April 11, 1892. Serial No. 428,698. (No model.)

To all whom it may concern:

Be it known that I, AUGUST OTTO TANNENBERG, a citizen of the United States, residing at New Orleans, in the parish of Orleans and 5 State of Louisiana, have invented certain new and useful Improvements in a Combined Side and Center Brace Attachment for a Step-Ladder; and I do declare the following to be a full, clear, and exact description of the invention, such as will enable others skilled in the art to which it appertains to make and use the same.

My invention relates to an improvement in a combined side and center brace attachment 15 for a step-ladder, and its novelty will be fully understood from the following description and claims, when taken in connection with the annexed drawings; and the objects of my invention are to provide braces for a step-ladder that will enable same to be used without risk of injuring body or limbs of a person, and at same time provide a steady support for the step-ladder. I attain these objects by the mechanism illustrated in the accompanying 20 drawings, in which—

Figure 1 is a front view. Fig. 2 is a side view. Fig. 3 is a detail front view. Fig. 4 is a detail side view.

Similar letters refer to similar parts throughout the several views.

In the drawings, A refers to the front portion of a step-ladder; B, the rear part of a step-ladder, which is connected to the front part A by links b, as shown.

35 C are lateral braces attached on each side of A by means of suitable hinges, and when the step-ladder is in use are drawn out from the sides of the part A, as seen in the dotted lines in Fig. 1 and as shown in Fig. 2, thus giving an increased base for step-ladder.

D are metal braces, which are pivoted between plate E and hinge F, and are provided with slots for engaging a lug or projection on sides of rear portion of step-ladder B, thus 45 bracing the rear part of step-ladder and preventing it from collapsing or closing when in use. By the provision of the links b, in conjunction with the front and rear parts A and B and the slotted braces D, it will be per-

ceived that the part B may readily be folded 50 against the part A, the said part B being previously disconnected from the brace D by simply lifting the braces up and out of engagement with the lugs.

G are metal arms attached to sides of A by 55 means of pivots or other means and are provided with openings or holes a, as shown in Fig. 3, for engaging the headed lugs d on the braces C, and will enable said braces to be retained in a fixed position until disengaged. 60 These holes a are provided with the offsets c, as shown, to receive the shank of the headed lugs d and prevent a casual disconnection of the arms from the lugs of the braces. At a point on the part A, designated H, I place 65 two eyes, which are secured in the usual manner and between which the eye K on brace C rests when the step-ladder is folded or the braces are not in use, and by simply inserting a piece of wire or nail through eyes H and K 70 a secure fastening is made. The hinges F of braces C are held in position by means of a pivot rigidly attached to plate E, said pivot also engaging arms D, which rest on plate E.

In practice the step-ladder is used in the 75 same manner as usual, except when in position, when the braces C are drawn out and engage the arms G in the manner shown in Fig. 3, thus giving an increase of base and steadiness to a step-ladder, while the braces 80 D engage the rear portion of a step-ladder.

A striking advantage of my invention is its economical construction and security from injury offered in use of same.

Having described my invention and the 85 manner in which the same is or may be carried into effect, I would say in conclusion that I do not limit myself to the precise details herein described, as the same may be varied to some extent; but

What I claim, and desire to secure by Letters Patent, is—

1. In a step-ladder, the combination, with the front part A, the rear part B, having lateral studs, and the links b, connecting the 95 rear part to the front part, of the braces D, pivotally connected to the front part A and having notches or slots in their lower edges

at intermediate points in their length to engage the lateral lugs of the part B, substantially as and for the purpose set forth.

2. In a step-ladder, the combination, with
5 the front part A and the rear part B, connected
to the front part, of the lateral braces C, hav-
ing their upper ends flexibly connected to
the sides of the front A and also having the
lateral headed lugs d and the arms G, pivot-
ally connected to the front part A and hav-

ing the holes a at intermediate points in its
length provided with the offsets c, substan-
tially as and for the purpose set forth.

In testimony whereof I affix my signature in
presence of two witnesses.

AUGUST OTTO TANNENBERG.
